Klaus P. Stoffel(57) CLAIM

The ornamental design for a pasta maker, as shown and described.

DESCRIPTION

FIG. 1 is a front view of a pasta maker of the present invention;

FIG. 2 is a rear view thereof;

FIG. 3 is a top view thereof;

FIG. 4 is a bottom view thereof;

FIG. 5 is a left side view thereof; and,

FIG. 6 is a right side view thereof.

In the drawings, the broken lines showing portions of a pasta maker depict environment and form no part of the claim.
